C. HAMMER,
BOTTLE CLOSURE.
APPLICATION FILED OCT. 19, 1918.

1,345,363.

Patented July 6, 1920.

Inventor:
Charles Hammer,

By his Attorney

Wm. J. Reid.

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BOTTLE-CLOSURE.

1,345,363.

Specification of Letters Patent.

Patented July 6, 1920.

Application filed October 19, 1918. Serial No. 258,879.

To all whom it may concern:

Be it known that I, CHARLES HAMMER, a citizen of the United States, residing at Queens, in the county of Queens and State 5 of New York, have invented certain new and useful Improvements in Bottle-Closures, of which the following is a specification.

This invention has reference to the construction of articles of a cup-shaped form, 10 particularly those used for the closures of bottles and similar containers.

The object of the present invention is to provide in such a construction, an improved form of the side joint and the bottom edge 15 at the open end, whereby the meeting edges of the blank strip from which the body of the closure is formed, will be interlocked to conceal the raw edge, and the same condition applies to the lower edge, so that no raw 20 edge is exposed, and a smooth finish is provided on the bottom of the closure.

In the accompanying drawing showing one embodiment of my invention, Figure 1 shows the blank for the body or cylindrical 25 member. Fig. 2 shows the blank in edge view with the end portions bent over previous to engagement. Fig. 3 is a side view of the blank as shown in Fig. 2. Fig. 4 is a side elevation of the body member bent to a 30 cylindrical form with the bent end portions engaged. Fig. 5 is a sectional view of the same, showing the interior. Fig. 6 is a vertical section of the finished closure; Fig. 7 shows enlarged a cross section of the interlocked joint at an intermediate portion of the closure.

As shown the blank comprises a strip 8 of thin sheet metal having at one end a projecting tongue 9, with notched corner portions at 10 and 11, the latter extending a greater distance inward from the end of the tongue. This tongue 9 is bent back against the inner face 12 of the blank for a distance equal to the notch 10, that will bring the 45 edge of the tongue 9 adjacent the edge 13 of the notch 11, as shown in Fig. 3.

At the other end of the blank 8 is a notch 14 at one corner of suitable depth. At the opposite corner is a short notch 15, and a short distance back is formed a notch or 50 opening 16, whose middle portion is on a transverse line with the inner wall 17 of the notch 14.

This end of the blank is first bent back on 55 the inner face 12, along the line 18 at the

end of the notch 14, and then the end portion is bent outward toward the extremity of the blank on a line 19 at one end of the notch 16. It will be observed that between this notch 16, and the corner notch 15 is a projecting 60 portion or tongue 20. At the extreme end of the blank it is again bent on a line 21 at the outer edge of the tongue 20. Thereby is formed a kind of channel, as indicated in Figs. 2 and 7. Into this channel is inserted 65 the bent edge or tongue 9 at the other end of the blank, by bending the blank to a cylindrical form, and these parts are pressed together as indicated in Fig. 7. It will be seen from Figs. 4 and 5 that as thus formed 70 the tongue 20 will project downwardly beyond the lapping joint, that is of less width than the width of the main portion of the blank. At the upper portion of the blank a slight angular opening 21 is formed. This 75 marginal portion beyond the interlocking joint is caused to engage the margin of a disk 22 forming a top for the closure. At the other end of the closure the margin is bent outwardly or rolled to form a bead 23, 80 that includes the portion beyond the interlocking joint. The tongue portion 20 is also bent outwardly or rolled and will be in substantial alinement or register with the other rolled or beaded portion as shown in Fig. 6. 85 This will make a smooth and even bottom edge, that could not be done if the interlocking joint extended down and was rolled or beaded in the same manner. With the tongue only a single thickness is bent over to form 90 the bead, as with the margin of the blank beyond the joint.

This structure forms a very strong and tight interlocking joint for the body, at the same time avoids a bulge or enlargement 95 where the lower edge is formed into a bead.

What I claim is:

1. A bottle closure comprising a body formed of a metal strip bent in the form of a cylinder with the ends secured together, such securing means comprising one end of the strip being bent back inwardly to form a channel, the other end being first doubled back flat on itself on the inside, with the end portion bent forward to form 100 a channel that has the edge bent inward a short distance, the said other bent edge being inserted in said channel portion to have its bent edge engaged in the said bent edge and all said bent portions being flat- 110

tened together to interlock with the edges concealed in the joint, said body having the top and bottom margins extended beyond the said joint, a disk closing one end 5 of the body that has its margins interlocked with said extension of the body, the open end of the closure having the projecting margin bent back outwardly to form a bead, the said strip having an extension at the 10 joint that is bent outwardly to form a part of said bead at the open end.

2. A bottle closure comprising a body formed of a metal strip bent in the form of a cylinder with the ends secured together, 15 such securing means comprising one end of the strip being bent back inwardly to form a channel, the other end being first doubled back flat on itself on the inside, with the end portion bent forward to form a channel 20 that has the edge bent inward a short distance, the said other bent edge being inserted in said channel portion to have its bent edge engaged in the said bent edge and all said bent portions being flattened together 25 to interlock with the edges concealed in the joint, said body having the top and bottom margins extended beyond the said joint, a disk closing one end of the body that has its margins interlocked with said extension 30 of the body, the open end of the closure having the projecting margin bent back outwardly to form a bead, the said strip having an extension at the joint that is bent outwardly to form a part of said bead at 35 the open end to conceal the raw edges and that constitutes an extension of the inner portion of the interlocking joint.

3. A bottle closure comprising a body formed of a metal strip bent in the form of a cylinder with the ends secured together, 40 such securing means comprising the end portion of the strip being bent back and interlocked to conceal the edges in the joint, said body having the top and bottom margins extended beyond the said joint, 45 a disk closing one end of the body that has its margins interlocked with said extension of the body, the open end of the closure having the projecting margin bent back outwardly to form a bead, the said strip 50 having an extension at the joint that is bent outwardly to form a part of said bead at the open end to conceal the raw edges, and that constitutes an extension of the inner portion of the interlocking joint. 55

4. A bottle closure comprising a body formed of a metal strip bent in the form of a cylinder with the ends secured together, such securing means comprising the end portion of the strip being bent back 60 and interlocked to conceal the edges in the joint, said body having the top and bottom margins extended beyond the said joint, a disk closing one end of the body that has its margins interlocked with said extension 65 of the body, the open end of the closure having the projecting margin bent back outwardly to form a bead, the said strip having an extension at the joint that is bent outwardly to form a part of said bead 70 at the open end to conceal the raw edges.

Signed at New York city, N. Y., on Oct. 17th, 1918.

CHARLES HAMMER.
